US0D1053320S

(12) **United States Design Patent** (10) **Patent No.:** **US D1,053,320 S**
(45) **Date of Patent:** **** Dec. 3, 2024**

(54) **FITTING**

(71) Applicant: **Quick Fitting Holding Company, LLC**, East Providence, RI (US)

(72) Inventors: **Libardo Ochoa Dias**, West Warwick, RI (US); **Matthew J. Boucher**, Houston, TX (US)

(73) Assignee: **Quick Fitting Holding Company, LLC**, East Providence, RI (US)

(**) Term: **15 Years**

(21) Appl. No.: **29/810,787**

(22) Filed: **Oct. 8, 2021**

(51) **LOC (14) Cl.** **23-01**

(52) **U.S. Cl.**

USPC **D23/262**

(58) **Field of Classification Search**

USPC D23/213, 233-237, 245, 259, 262-263, D23/265-266; D8/382, 396-397;

D15/21

(57) **CLAIM**

The ornamental design for a fitting, as shown and described.

DESCRIPTION

FIG. 1 is a top right front perspective view of the fitting of our new design;

FIG. 2 is a right side elevational view of the fitting of FIG. 1;

FIG. 3 is a left side elevational view of the fitting of FIG. 1;

FIG. 4 is a front elevational view of the fitting of FIG. 1;

FIG. 5 is a rear elevational view of the fitting of FIG. 1;

FIG. 6 is a top plan view of the fitting of FIG. 1; and,

FIG. 7 is a bottom plan view of the fitting of FIG. 1.

The dashed broken lines depict portions of the fitting that form no part of the claim.

1 Claim, 7 Drawing Sheets
